UNITED STATES PATENT OFFICE.

JAMES G. ENGLISII, OF NEW HAVEN, CONNECTICUT, ASSIGNOR TO ENGLISH & MERSICK, OF SAME PLACE.

DESIGN FOR A HUB-BAND.

SPECIFICATION forming part of Design No. 21,625, dated June 21, 1892.

Application filed April 4, 1892. Serial No. 427,751. Term of patent 14 years.

To all whom it may concern:

Be it known that I, JAMES G. ENGLISH, of New Haven, in the county of New Haven and State of Connecticut, have invented a new 5 Design for Hub-Bands for Carriage-Wheels; and I do hereby declare the following, when taken in connection with accompanying drawing and the letters of reference marked thereon, to be a full, clear, and exact description of 10 the same, and which said drawing constitutes part of this specification, and represents a perspective view.

This invention relates to a design for the bands which are applied to the outer ends of 15 carriage-wheel hubs; and the design consists in the ornamentation of the outer surface of the band, as shown in the accompanying illustration.

The body of the band is represented as of

plain cylindrical shape, and around the outer 20 surface of the band is the representation of beads, giving the appearance of annular projecting ribs, the ribs represented as substantially semicircular in transverse section, and the periphery of the ribs presenting a milled 25 appearance, as shown in the accompanying illustration.

I claim—

The design for a hub-band, as herein shown and described.

In testimony whereof I have signed this specification in the presence of two subscribing witnesses.

JAMES G. ENGLISII.

Witnesses:

C. T. LINCOLN,
JOHN MACKAY.
